UNITED STATES PATENT OFFICE.

THOMAS C. HOLT, OF MINNEAPOLIS, MINNESOTA, ASSIGNOR OF ONE-HALF TO THEODORE DUNN, OF MINNEAPOLIS, MINNESOTA.

CONCRETE-BLOCK MACHINE.

No. 821,842.

Specification of Letters Patent.

Patented May 29, 1906.

Application filed May 18, 1905. Serial No. 260,921.

To all whom it may concern:

Be it known that I, THOMAS C. HOLT, a citizen of the United States, residing at Minneapolis, in the county of Hennepin and State of Minnesota, have invented certain new and useful Improvements in Concrete-Block Machines; and I do hereby declare the following to be a full, clear, and exact description of the invention, such as will enable others skilled in the art to which it appertains to make and use the same.

My invention has for its object to provide an improved machine for molding concrete building-blocks; and to this end it consists of the novel devices and combinations of devices hereinafter described, and defined in the claims.

The invention is illustrated in the accompanying drawings, wherein like characters indicate like parts throughout the several views.

Figure 1 is a plan view of the improved molding-machine. Fig. 2 is a view, partly in side elevation and partly in vertical section, on the irregular line $x^3 x^2$ of Fig. 1. Fig. 3 is a view, partly in elevation and partly in vertical section, on the line $x^3 x^3$ of Fig. 1; and Fig. 4 is a detail showing one of the adjustable hinged brackets.

The numeral 1 indicates a table or bed-plate supported by legs 2, which legs are tied together by horizontal bars 3. The table 1 has a large rectangular central opening 4 and is formed with slots 5 and 6. A rigidly-sealed split bar 7 extends transversely across the rectangular opening 4. The table 1 at the edges of the opening 4 and extending at a right angle to the split bar 7 is formed with depressed guide-flanges 8, that afford a supporting-track for the ends of adjustable bars 9, which bars are adapted to be secured in different set positions. The adjustable bars 9 are provided with hinged lugs 10.

The molding-flask illustrated is constructed to form two blocks at one time, and hence a vertical movable partition-plate 11 is arranged to work through the slit in the split bar 7. At its ends this partition-plate 11 is formed with depending cross-heads 12, that work in vertically-disposed channel-guides 13, rigidly secured on the adjacent frame-bars 3. The flask is provided with four side plates, which for distinction may be design-

nated as side plates 14 and end plates 15. The side plates 14 are provided with lugs 16, 55 that are pivotally connected by pins 17 to the hinged lugs 10 of the adjustable bars 9. At their ends said side plates 14 are provided with flanges 18, that are adapted to engage and hold the end plates 15, as best shown in Fig. 1. The end plates 15 are provided with hinge-lugs 19, that are pivotally connected by pins 20 to hinge-brackets 21, which hinged brackets are provided with nuts 22, by means of which they may be secured in their set position. The end plates 15 are provided with latch-hooks 23, that engage with lugs 24 on said plates 14 to hold the latter in the vertical position, as shown in the drawings. As shown, said plates 15 are formed with vertical 65 grooves 15^a, in which the ends of the partition-plate 11 are arranged to slide.

The numeral 25 indicates detachable mold-boards that form temporary bottoms to the compartments of the flask and are loosely supported by the fixed and adjustable bars 7 and 9, respectively. As shown, these boards 25 are made up each of two vertically-spaced boards separated by spacing-strips, said parts being nailed or otherwise secured together.

To form the concrete blocks hollow or with air-spaces, vertically-movable cores 26 are provided. These cores 26 work through openings in the mold-boards 25 and are rigidly secured to vertically-movable bars 27, which bars at their ends are provided with depending cross-heads 28, that work in vertical channel-guides 29. The channel-guides 29 are mounted for lateral adjustments toward and from the partition-plate 11, this adjustment, as shown, being accomplished by means of nut-bolts 30, that work in slots 31, formed with the adjacent frame-bars 3.

For simultaneously raising and lowering both of the core-supporting bars 27 and the partition-plate 11 I provide a lifting-bail 32, the trunnions of which are journaled, the bearings 33 secured to the adjacent frame-bars 3. One of the trunnions of said lifting-bail has rigidly secured to it a latch-lever 34, that cooperates with the notched latch-segment 35, attached at its upper end to the table 1. The transverse body or crank portions of the lifting-bail 32 directly engage 85 with the central lower portions of the two

core-supporting bars 27 and of the partition-plate 11, so that by vertical movements of said bail the said cores and partition may be moved upward and positively held in their operative positions, as shown in the drawings. In order that a downward movement of the said bail will positively force downward the cores 26 and the partition-plate 11, both of the bars 27 and the partition-plate 11 are provided with yokes 36, that extend under and embrace the body portion of said lifting-bail.

By adjustments of the bars 9 the width of the blocks formed in the flask may be varied, and such adjustment, as is obvious, will require adjustments of the channel-guides 29, so as to locate the cores 26 always at the transverse center of the block. For blocks of different width different end plates should be used. By adjustments of the hinged brackets 21 in the slots 6 the length of the blocks may be varied, and for such adjustments different side plates 14 and partition-plates 11 should be employed. For extremely wide blocks the adjustable bars 9 may be dispensed with, and the side plates 14 may be hinged to additional brackets 21, provided for that purpose and applied in the grooves 5 of the table in the same manner as shown and before described in connection with the slots 6. The several slots 6 afford means for the application of hinge-brackets 21 to fit and support end plates of different length.

The machine above described has been constructed and put in actual use and has been found extremely efficient for the purposes had in view. With this machine two blocks may be formed as quickly as a single block can be formed in other machines.

From what has been said it will be understood that the machine is capable of modifi-

cation within the scope of my invention as herein set forth and claimed.

What I claim, and desire to secure by Letters Patent of the United States, is as follows:

1. The combination with a molding-flask, of a vertically-movable partition-plate working in said flask, a pair of vertically-movable bars having cores working in the compartments of said flask, and a lifting-bail having an actuating-lever and operative on said partition-plate and on said core-supporting bars, to simultaneously raise and simultaneously lower the same, substantially as described. 55

2. The combination with a molding-flask having separable and laterally-adjustable side plates and a vertically-movable partition-plate, of vertically-movable bars provided with cores working in the compartments of said flask, vertically-disposed laterally-adjustable guides in which the ends of said core-supporting bars work, and a lever-actuated lifting-bail operating on the said partition-plate and on said core-supporting bars to simultaneously raise and simultaneously lower said partition-plate and said cores, substantially as described. 60

3. The combination with a molding-flask, of a dividing-partition in said flask, a pair of vertically-movable cores working in the compartments of said flask, guides for said cores arranged for lateral adjustments so as to move the cores bodily, toward and from said partition-plate, and means for simultaneously moving said cores into working positions and from working positions, substantially as described. 70

In testimony whereof I affix my signature in presence of two witnesses.

THOMAS C. HOLT.
